UNITED STATES PATENT OFFICE.

THOMAS BROWN, OF THURLOW, PENNSYLVANIA.

RAILROAD-TIE.

SPECIFICATION forming part of Letters Patent No. 451,804, dated May 5, 1891.

Application filed January 17, 1891. Serial No. 378,104. (No model.)

To all whom it may concern:

Be it known that I, THOMAS BROWN, a citizen of the United States of America, residing at Thurlow, in the county of Delaware and State of Pennsylvania, have invented certain new and useful Improvements in Railroad-Ties; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

This invention relates to improvements in metallic railway-ties.

The object of the invention is to provide a tie made up substantially of a single casting having raised and hollow end portions, which are wedge-shaped in cross section and adapted to receive a wooden block, upon which the rail rests and is spiked, said block being retained in place by end plates, which are bolted to the metallic tie, as will be hereinafter fully set forth and particularly claimed.

In the accompanying drawings, forming part of this specification, Figure 1 is a side view of a metallic tie constructed in accordance with my invention, one end of the same being broken away. Fig. 2 is a section on the line $\alpha\alpha$ of Fig. 1. Fig. 3 is a plan view. Fig. 4 is a section of a modification.

A refers to a casting, which comprises a base-plate a , raised end portions B , and a central web C . The raised end portions present receptacles wedge-shaped in cross-section for the reception of wedge-shaped blocks E , said blocks being preferably made of wood. These blocks are held in place by end plates D , which

have perforated projections which register with lugs b , formed at the ends of the raised portions B , bolts being employed for securing the parts, as shown. The rails T rest upon the wooden blocks E and are spiked thereto in the usual manner, and when said blocks are worn out they can be removed and new ones inserted without destroying the tie or removing it from the road-bed. The plates D may be cut away at their lower edges or be shortened to not rest upon the base-plate a , so that moisture which may collect in the receptacles can pass out.

Instead of having the receptacles wedge-shaped, the side walls may be made parallel and the upper ends thereof extended inward.

I am aware that prior to my invention it has been proposed to construct a railway-tie of metal and provide the same with boxes to receive wooden blocks, to which the rails are secured, and I do not, therefore, claim such construction, broadly, as my invention; but

What I do claim as new, and desire to secure by Letters Patent, is—

In a metallic railway-tie, a casting presenting a base a , wedge-shaped boxes B , having open outer ends and tops, perforated lugs b , formed thereon, and vertical connecting-flange C , together with retaining-plates D , connected to the casting by bolts to close the outer ends of the boxes and retain therein blocks E , substantially as set forth.

In testimony whereof I affix my signature in presence of two witnesses.

THOMAS BROWN.
